UNITED STATES PATENT OFFICE.

HARVEY E. KAHLER, OF AURORA, ILLINOIS.

MEANS FOR BRACING THE CHASSIS-FRAMES, RUNNING-BOARDS, AND FENDERS OF AUTOMOBILES.

1,295,904.

Specification of Letters Patent.

Patented Mar. 4, 1919.

Application filed December 11, 1917. Serial No. 206,582.

To all whom it may concern:

Be it known that I, HARVEY E. KAHLER, citizen of the United States, and a resident of the city of Aurora, in the county of Kane and State of Illinois, have invented certain new and useful Improvements in Means for Bracing the Chassis-Frames, Running-Boards, and Fenders of Automobiles, of which the following is a full, clear, and exact specification.

This invention relates to improvements and means for bracing the chassis frame, running board and fenders of automobiles, and more particularly as they are constructed and arranged in the "Ford" automobile in which heretofore the sole support of the running board is located toward their respective ends and consists of brackets riveted to, and depending from, the side bars of the chassis frame, provided with downwardly projecting lugs, connected at each side of the frame in pairs, by means of transverse rods, adjustable by means of nuts screw-threaded thereon, and between which the depending lugs are clamped.

In practice, however, it is found that the rods bend, and remain bent, under the weight imposed upon the running board from the passengers entering and leaving the machine, with the result that the running boards tilt downward at their outer edges, and under the most favorable conditions produce objectionable vibrations throughout the chassis, further increased by the bending of these connecting rods.

The prime object of my invention, broadly stated, is to provide a means of directly bracing the side bars and supporting the running boards of a chassis, the construction of which is such that the chassis frame is substantially and materially stiffened, the running boards are maintained against tilting, and the chassis, as a whole, prevented from objectionable vibrations.

More specifically stated, the object of my invention is to provide a brace for the side bars and support for the running boards of a chassis, which, when located in its operative position, may be so sprung as to materially stiffen the side bars and maintain the running boards against tilting without rendering either the running boards or the frames absolutely rigid against compression strains to which either may be subjected.

Another object of my invention is to provide a brace for the frame and a support for the running boards, extending transversely across the side bars of the frame and about the middle of the running boards, extending in parallel lines outwardly and beyond the side bars the ends of which beneath the running boards diverge sufficiently to form a substantially broad support for the running boards, and whereby such brace may be suspended from the side bars and adjusted in its operative position in the absence of any necessity for perforations through the brace.

A further object of my invention is to provide a brace performing the functions above described, constructed with minimum cost consistent with the strength and durability necessary for producing results attributed thereto, and which may be conveniently and quickly secured in its operative position on a "Ford" automobile without any change therein other than the substitution of a wood board for the blocks in the running board heretofore employed as a support between the end and supporting the brackets for the running board.

With these ends in view my invention finds its embodiment in certain features, novelty in the construction, combination, and arrangements of parts by which the said objects, and certain other objects, are attained but is hereinafter further described in the accompanying drawings and more particularly pointed out in the claims.

In said drawings:

Figure 1 is a top plan view of a chassis, in which my invention finds its embodiment, in its operative adjusted position.

Fig. 2 is a longitudinal section on the line 2-2 of Fig. 1.

Fig. 3 is a detailed transverse section taken on the line 3-3 of Fig. 1.

Fig. 4 is a section taken on the line 4-4 of Fig. 3.

Fig. 5 is a similar view showing the bend in the brace and the position of the running board thereon before the brace is subjected to tension, and—

Fig. 6 is a transverse section through the side bars showing the present rod and bracket construction in a "Ford" automobile.

As commonly constructed, the chassis of a "Ford" automobile is provided with a frame,

the side bars 5 and 6 of which are of channel iron connected adjacent to their ends by means of side bars 7—7, and running boards 8 and 9, furnishing an end support for fenders 10—10.

The running boards 8 and 9 are of sheet steel in the form of channels, and are supported toward their ends respectively by brackets 11—11 and 12—12.

10 Riveted to the side bars, as indicated at 12^a, Fig. 2, and depending therefrom; the brackets are each provided with a lug and are connected in pairs transversely of the frame by rods 14—14, secured in the lugs 13 by means of nuts 15—16, screw-threaded on the rods 14, and embracing the lugs 13.

15 The running board is secured to the brackets by means of bolts 17^a, which bolts pass through narrow blocks not shown, fitting between the flanges of the running board on a line with the bracket supports.

20 The rods connecting the brackets have no tendency to brace or stiffen the frame as a whole and so little upon the brackets that 25 in a short time the rods bend and, as a result thereof, the brackets being made of malleable iron, they bend downwardly and accordingly tilt the running boards, the bending of the brackets being due to the weight 30 of the occupants on the running board in making their entrance to and exit from the automobile, and which is more or less aggravated by the frequency in which occupants some times jump on the running 35 board. It will, therefore, be apparent that any means by which the running boards may be maintained against tilting and the frames so braced as to eliminate objectionable vibrations will be a material and substantial improvement in the art.

40 In carrying out my invention I arranged two stock channel beams 17 and 18, and, after bending their respective extreme ends 19—19 and 20—20, as indicated in Fig. 1, 45 spaced them apart by means of blocks 23, adjacent to their bent ends, and secured the channel beams and blocks together by means of rivets 24, thereby providing sufficient space between the channel beams for the 50 passage of the shank 25 of hooks 26, which are respectively adapted to hook over upon the side bars 5 and 6, as indicated in Fig. 3, for suspending the bent ends of the bars in a plane next below that of the running 55 boards.

55 The ends of the opposing bars 17 and 18 are bent in opposite directions and of a sufficient distance apart to form an accordingly base support for the running boards, as indicated in Fig. 5, which spread-apart ends are also bent upwardly at a slight angle with reference to the upper surface of the parallel portions of the bars.

60 The shanks 25 of the hooks 26 project between and below the side bars 5 and 6 and

are provided with screw threads 27 for nuts 28 and 29 respectively above and below the bars, and provide for an adjustable fulcrum, the weight for which is the running boards. By tightening the nuts 29 until the resistance offered by the running boards bolted as they are to the brackets at their opposite ends, the upward bend in the arms may be straightened out more or less, and, in any event, until the running boards are substantially flattened upon the branching arms, as indicated in Fig. 3.

65 The running boards are stiffened by means of a plank 30, extending the length of the running boards, and filling in the entire 80 space between the depending flanges of the running boards, which planks serve to stiffen the running boards and distribute throughout the running boards the force exerted and concentrated against them by the 85 diverging arms.

70 It is now to be observed that the force, produced by the tightening of the nuts 29, against the parallel bars, until the upper bend in the arms, as shown in Fig. 5, is 90 straightened out as indicated in Fig. 3, imparts to the parallel bars of the brace a tendency tending to slightly curve both bars in an upward direction from end to end, and with a result that the straight portions of 95 the brace form a trussed structure operating to resist the bending of its diverging arms below the plane, to which they are bent from their normal position, and this without making the running boards absolutely rigid 100 or preventing them from yielding sufficiently and to a desirable degree when subjected to the weight of the occupant.

75 In conclusion, it is noted that for the embodiment of my invention other cross sectional forms of bars than are shown and described may be employed for the construction of the brace, or the same forms in different positions, and that it would not be a substantial departure from my invention 110 to construct the brace bar from a single beam split at the ends, although, from the commercial standpoint, a two-piece spaced base bar is provided for the reason that the necessity of perforating the same for the 115 passage through of the hook hangers is avoided, while, at the same time, the greatest assistance is given to the brace as a whole by the employment of separate bars spaced apart by blocks and secured by rivets.

80 Having described my invention, what I claim and desire to secure by Letters Patent is:

1. A brace support for the chassis of automobiles, comprising a bar the sides of which diverge and adjacent the ends thereof forming a broad support for the running boards, means for suspending said bar from the chassis frame and connecting the running boards therewith, and means for flexi- 130

bly curving said bars in an upward direction and bending their end portions in the opposite directions.

2. A brace for the chassis of automobiles, comprising spaced parallel bars, the end portions of which are spread apart to form a support for the running board, means for suspending said bars from the chassis frame, and means for flexibly trussing said bars.
- 10 3. A brace for the chassis of an automobile, comprising spaced parallel bars, diverging laterally and bent upwardly toward their ends and forming a support for the running boards, means for attachably suspending said bars from the side bars of the chassis frame, and means for adjustably flexing the bars upwardly, and, concurrently therewith, the outer end thereof to approximately a horizontal plane.
- 20 4. A brace for the chassis of an automobile, comprising spaced channel bars, means for rigidly connecting said bars, the ends of which bars are spread apart and inclined upwardly, means for suspending said bars from the chassis frame, and means for adjustably flexing the straight portions of said

bars upwardly, and the upwardly bent end downwardly, to a plane approximately that of the straight portions of the bars, whereby the frame is substantially stiffened, and the running boards are permanently maintained against tilting.

5. A brace for the chassis of an automobile, comprising parallel spaced channel bars, means for rigidly connecting said bars, hooks adapted for suspending said bars from the side bars of the chassis frame, the shanks of which hooks project between said bars, the outer ends of which bars are spread apart and support the running boards about midway of their length, and means for flexing said bars at intervals of their length, whereby the frame is stiffened and the running boards maintained against tilting.

In witness whereof, I have hereunto set my hand and affixed my seal this eighth day of December A. D. 1917.
